UNITED STATES PATENT OFFICE

LEO DEUTSCH, OF BEAVER, PENNSYLVANIA, ASSIGNOR, BY MESNE ASSIGNMENTS, TO
THE WAYNE PUMP COMPANY, OF BALTIMORE, MARYLAND, A CORPORATION OF
MARYLAND

SIGHT-VALVE ASSEMBLY

Application filed July 18, 1927. Serial No. 206,572

This invention pertains to a dispensing valve and more particularly a sight valve for positively indicating amounts of fluid which may be contained in a reservoir or in the communication between said reservoir and said valve.

With the ordinary type of discharge valve now in use on devices such as pumps, dispensing apparatus or the like, it is possible to prematurely shut the discharge valve to retain a quantity of the fluid within the dispensing device, there being no way to check up to ascertain if the full amount has been delivered unless said valve is opened again.

It is therefore an object of this invention to provide a means whereby the amount of fluid in a container, or the connection between a container and the dispensing valve, may be readily ascertained.

Another object is to provide a fluid indicating means cooperating with a discharge valve and so disposed that the indicating means is operative at all times.

Still another object is to provide an inexpensive and readily accessible valve having indicating means associated with parts of the valve for determining amounts of fluid in a reservoir or connection between the reservoir and valve.

30 A further object is to provide a sight valve particularly adaptable for fluid dispensing devices whereby fluid levels are readily discernible, means being provided whereby the levels may be determined by a plurality of means.

Still another object is to provide an assembly including castings, preferably fabricated, for readily and positively indicating fluid level at all times in a device.

40 Other, further and more specific objects will readily occur from the following detailed description, claims and drawings appended hereto.

In the drawings, wherein like reference characters are used to designate like parts—

Figure 1 is a side elevation of the sight valve assembly with the valve in closed position;

Figure 2 is a top plan view of the valve assembly shown in Figure 1;

Figure 3 is a fragmentary sectional elevation taken substantially on the plane as indicated by the line 3—3 of Figure 2;

Figure 4 is a top sectional plan taken substantially on the plane as indicated by the line 4-4 of Figure 1; 55

Figure 5 is a partial sectional elevation taken substantially on the plane as indicated by the line 5—5 of Figure 4, and

Figure 6 is a sectional end elevation taken substantially on the plane as indicated by the line 6—6 of Figure 2.

In the valve 10, which may be of any suitable material depending more or less upon the fluid to be dispensed, the valve casing 11 is provided with a suitable channel or passage 12 suitably threaded at one end at 13 for co-operation with corresponding threads on a pipe 14 communicating with the valve and a fluid reservoir or source such as the measuring chamber of a fluid pump. The other end of the passage 12 is preferably depressed with respect to the pipe 14 and is suitably threaded at 15 for the reception of the fastening collar 16 providing a fastening and pivotal connection between the valve and a suitably threaded discharge nozzle 47. The passage 12 is preferably provided with a double valve seat, the upper portions 17 and 17^a of said seats being spaced farther apart than the lower portions 18 and 18^a thereof. A member 19 is provided with closing means adapted to cooperate with the valve seats, said means comprising valve discs 19^b and 19^c carried by member 19 and adapted to cooperate 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530

fixed by member 19 and adapted to cooperate with the seats 17-18 and 17a-18a. The member 19 is pivoted at a point removed from the valve discs, to an operating shaft 20 provided with the operating handle 21, which shaft is carried by and pivoted in a suitable gland or stuffing box 22 which may be part of and adjacent the valve chamber 23 disposed above the valve seat and into which the member 19 travels in order to open communication through the channel 12. It will be noticed that due to the angle between the valve seats and due to the shape of the valve discs and the fact that they are loosely carried by the member 19, a closing action will tend to wedge the valve discs into tighter

contact with the valve seats, thereby doubly preventing leakage through the valve. The top of the valve chamber is suitably threaded at 24 and a threaded cap 25 is provided for accessibly closing the valve chamber, said member being provided with a disc 26 overlapping the chamber.

On the other side of the passage 12, sight indicating means such as chambers 27 are provided, said means comprising bottom and top spaced supports 28 and 29, said supports carrying an open ended transparent cylinder of suitable material such as glass, said material being protected by spaced bars 31 running between and carried by the top and bottom supports. Said cylinder is adapted to be removably secured in place in the supports by means of a threaded washer 32 threaded to the top 29 and 29^a, there being provided suitable shoulders 32^a in the bottom support for positioning the glass. The top support is suitably threaded at 33 and is provided with a correspondingly threaded cap 34 similar to the cap 25 and provided with the disc 35 overlapping the chamber 27. The chambers 27 are preferably connected by a passage or core 36, which core communicates through the port 37 directly with a portion of the valve passage connected to the pipe 14. Communicating with the indicating chambers and the valve chamber are suitable cores or passages 38 preferably provided adjacent the top of said chambers clear of caps or other members.

It will be readily understood that when the handle 21 is actuated (raised), the member 19 and consequently the valve discs 19^b and 19^c are raised from their respective seats, allowing communication with the pipe 14 through the passage 12, through the swiveled nozzle 47 to a suitable draw-off hose, it being understood that due to port 37 and the passage 36, fluid will rise and be shown in the chambers 30. If then the valve 19^a is closed before the pipe 14 is fully exhausted, the fluid will pass through port 37, through the core 36 and will rise in chambers 27 indicating the level and consequently the amount of fluid remaining in the pipe 14, it being noticed that due to the passages or cores 38 there will be no vacuum or fluid pressure formed above the fluid disposed in chambers 27, preventing registering or preventing flow of fluid from said chambers when the valve 19^a is open.

It will be readily appreciated that a valve of this general nature is rugged, inexpensive and positive of operation, yet should any part excessively wear or be broken, new parts can be readily substituted by merely removing the parts disposed in way of said worn or broken parts.

I do not wish to be limited by the exact embodiment of the device shown as other and various forms of this device will readily occur to those skilled in the art. For instance,

it will be readily appreciated that any form of gauges may be applied in place of the indicating chambers 27, it being possible to install such gauges as will indicate any quantity of fluid desired; that is, any quantity of fluid contained either in the discharge pipe 14 or in the reservoir connected to said pipe, it being therefore possible to provide a discharge valve that will serve two functions, namely, of indicating the total amount of liquid to be dispensed or in the measuring chamber and any fluid retained during the dispensing operation.

I claim:

1. In a device of the character described, the combination of a valve chamber having a seat therein cooperating with a valve, means for closing communication regardless of the direction of flow through a passage through said valve chamber, and indicating means communicating with said passage and valve chamber.

2. In a device of the character described, the combination of a valve chamber having a seat therein cooperating with a valve, means for closing communication through a passage through said valve chamber, and indicating means communicating with said passage in front of said valve chamber to indicate the fluid in said passage even when said seat is closed and said indicating means communicating with said valve chamber.

3. In a dispensing valve, the combination of an outlet communicating with a discharge nozzle, a valve seat in said outlet, a valve chamber adjacent said seat, valve means in said chamber adapted to be operated to have closing engagement with said seat, and indicating means disposed on either side of said outlet and communicating with said outlet in front of said seat and with said valve chamber at a distance removed from said seat.

4. A discharge valve including a housing having a discharge passage therein, valve seats in said passage, valve means cooperating with said seats for controlling the flow of fluid through said passage, said valve means being adapted to be moved into an accessible valve chamber, fluid indicating means in said valve having communication with said discharge passage on the inlet side of said passage, said indicating means having communication with said valve chamber.

5. In a dispensing valve, the combination of an outlet communicating with a discharge nozzle, a valve seat in said outlet, a valve chamber adjacent said seat, valve means in said chamber adapted to be operated to have closing engagement with said seat, and indicating means adjacent and communicating with said outlet in front of said seat and with said valve chamber at a distance removed from said seat.

6. In a dispensing valve, the combination of an outlet communicating with a discharge

5 nozzle, a valve seat in said outlet, a valve chamber adjacent said seat, valve means in said chamber adapted to be operated to have closing engagement with said seat, and indicating means adjacent and communicating with said outlet in front of said seat and with said valve chamber at a distance removed from said seat and with said valve chamber above said seat.

10 7. In a dispensing device, the combination of a valve-controlled passage and indicating means communicating with said passage above and below said valve and adapted to show the presence of material in said passage regardless of the position of said valve.

15 8. In dispensing apparatus, the combination of a discharge passage and a plurality of indicating means for showing the amount of material in said passage, said means having communication with said discharge passage and with each other.

20 9. In dispensing apparatus, the combination of a discharge passage having a valve chamber therein, sight chambers for showing the amount of material in said passage, said chambers having communication with said discharge passage, with said valve chamber and with each other.

25 10. In dispensing apparatus, the combination of a discharge passage having a valve chamber therein, sight chambers for showing the amount of material in said passage, said chambers having communication with said discharge passage on the inlet side, with said valve chamber and with each other.

30 11. In dispensing apparatus, the combination of a housing having a discharge passage therethrough, the outlet side of said passage being lower than the inlet side, a valve chamber in said passage having a valve seat and a valve member adapted to cooperate with said valve seat to prevent discharge through said passage, indicating means for said passage located between said valve chamber and the outlet side of said passage and in communication with said passage between said valve chamber and the inlet side.

35 12. In dispensing apparatus, the combination of a housing having a discharge passage therethrough, the outlet side of said passage being lower than the inlet side, a valve chamber in said passage having a valve seat and a valve member adapted to cooperate with said valve seat to prevent discharge through said passage, and indicating means for said passage located between said valve chamber and the outlet side of said passage and in communication with said passage between said valve chamber and the inlet side, said indicating means being in communication with said valve chamber above said valve seat.

40 13. In dispensing apparatus, the combination of a housing having a discharge passage therethrough, a valve chamber in said passage

45 having a valve seat and a valve member adapted to cooperate with said valve seat to prevent discharge through said passage, a closure for said chamber, and visible indicating means for determining the amount of material in said passage, said means including supports, a transparent casing disposed between said supports, securing means therefor, and a closure for one of said supports, said supports being in communication with said passage and with said chamber.

50 14. In dispensing apparatus, the combination of a housing having a discharge passage therethrough, a valve chamber in said passage having a valve seat and a valve member adapted to cooperate with said valve seat to prevent discharge through said passage, a closure for said chamber, and visible indicating means for determining the amount of material in said passage, said means including supports, a transparent casing disposed between said supports, securing means therefor, a closure for one of said supports, and guards for said casing carried by said supports, said supports being in communication with said passage on the inlet side and with said chamber above said seat.

Signed at Rochester, Pennsylvania, this 13th day of July, 1927.
